US00D467453S

(12) United States Design Patent **(10) Patent No.:** **US D467,453 S**
Kwon **(45) Date of Patent:** **** Dec. 24, 2002**

(54) DESK LEGS

D420,527 S * 2/2000 Pinch et al. D6/429
D423,258 S * 4/2000 Pinch D6/499
D449,471 S * 10/2001 Petersen D6/495

(75) Inventor: **Dong-Yul Kwon, Seoul (KR)**

* cited by examiner

(73) Assignee: **Fursys, Inc., Seoul (KR)**

Primary Examiner—Janice E. Seeger
(74) Attorney, Agent, or Firm—Merchant & Gould P.C.

(**) Term: **14 Years**

(57) CLAIM

(21) Appl. No.: **29/151,756**

The ornamental design for desk legs, as shown and described.

(22) Filed: **Nov. 6, 2001**

DESCRIPTION

(51) LOC (7) Cl. **06-06**
(52) U.S. Cl. **D6/499**
(58) Field of Search D6/422–428, 495–499,
D6/480, 484, 487; 312/194–196, 208.1;
108/50.01, 50.02, 153.1, 156, 157.1, 161;
248/188.1, 188.6, 188.8

FIG. 1 is a perspective view thereof;
FIG. 2 is a rear view thereof;
FIG. 3 is a front view thereof;
FIG. 4 is a left side view thereof;
FIG. 5 is a right side view thereof;
FIG. 6 is a top elevational view thereof; and,
FIG. 7 is a bottom view thereof.
